A. R. Vennill
His ATTORNEY

UNITED STATES PATENT OFFICE

BERNARD E. O'HAGAN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Application filed August 20, 1930, Serial No. 476,574. Renewed April 9, 1931.

My invention relates to railway traffic controlling apparatus, and has for an object the protection of such apparatus from excessive currents that might be injurious.

I will describe one form of apparatus embodying my invention, and will then point out the novel features thereof in claims.

The accompanying drawing is a diagrammatic view, showing one form of apparatus embodying my invention.

Referring to the drawing, the reference character A designates a railway switch which is actuated by an electric motor M having an armature 1 and a field 2. Operatively connected with the switch is a cut-out controller MC comprising a contact arm 50 and contacts 3 and 4. Contact 50-3 is closed at all times except when the switch occupies its extreme reverse position, and contact 50-4 is closed at all times except when the switch occupies its extreme normal position.

The motor M is controlled in part by a circuit controller designated by the reference character P, and which is, in turn, controlled by a pole-changer L which may be incorporated in a switch lever of an interlocking machine. The circuit controller P comprises an electromagnet 9, made up of two windings 9^a and 9^b, and a polarized winding 10 which is preferably provided with a permanently magnetized core 11. Pivotaly attached to the core 11 is an armature 12 which is therefore polarized by flux from the permanent magnet core 11 at such times as winding 10 is not carrying current. It follows that when the electromagnet 9 is supplied with current of one polarity, the armature 12 will be swung in a clockwise direction, but that when current of the opposite polarity is supplied to electromagnet 9, the armature will be swung in the opposite direction. The armature 12 controls three pivoted contact yokes 13, 14 and 15 through suitable linkage in such manner that the yokes occupy their right-hand positions when the armature is swung to the left, and vice-versa.

The reference character B designates a neutral magnet which controls a pivoted armature 17, the lower end of which projects into the path of movement of a portion of

armature 12 to prevent reversal of the armature 12 when the neutral magnet B is deenergized. Pivotaly attached to the armature 17 is a link 19 provided with a slot 42 which at times engages a pin 43 in a rocker arm 70 which carries a contact finger 20. When magnet B is deenergized, the link 19 moves the rocker arm 70 against the bias exerted by spring 44 into a position in which the contact finger 20 connects wire 33 with wire 34. When neutral magnet B is energized, however, the spring 44 urges the rocker arm 70 into a position wherein the contact between wires 33 and 34 is interrupted.

The apparatus thus far referred to is illustrated and described in United States Letters Patent No. 1722364, granted to Henry S. Young on the 30th day of July, 1929, for railway traffic controlling apparatus.

The reference character R designates an automatic thermal overload circuit breaker. The circuit breaker R comprises a primary core 25 on which is a winding 23, and a secondary core 24 on which are windings 28 and 29. Winding 23 is connected in series with the motor circuit so that it carries the entire motor operating current. Windings 28 and 29 have a common terminal N which is connected to cut-out controller MC by wire 51. The other terminals of windings 28 and 29 are respectively connected to contacts 46 and 37 of thermal relays T and T¹. Armature 21 of the circuit breaker is normally held open by rod 27 due to the compression of spring 22 and the attraction of armature 26. When armature 21 is attracted, detent 57 will be raised, raising link 19 and thus disengaging slot 43 from pin 42 and opening contact 33-34. The parts of the circuit breaker R are so designed that as long as either of the two windings on core 24 is fully energized, the maximum amount of current that can be drawn by the switch motor, passing through coil 23, will not attract the armature 21 of coil 23 against the pull of the armature 26 by either coil 28 or 29.

As shown in the drawing, the switch A occupies its normal position; the neutral magnet B is deenergized thereby locking armature 12 of circuit controller P in its left-

hand position; and the pole-changer L on the switch lever occupies its normal position.

When the switch is to be moved to the reverse position, pole-changer L will be reversed, thereby reversing relay P. The motor circuit will then be from terminal BH of a source of current, through wire 7¹, wire 18, winding 23, wire 33, contact 20, wire 34, wire 30, yoke 13, flexible connector 54, wire 35, wire 36, armature 1, wire 41, wire 47, flexible connector 53, yoke 14, wire 45, thermal relay winding 18, contact 3, contact arm 50, and field 2 to terminal CH of the same source of current. The holding coil 29 associated with the motor circuit is connected across the armature 1 and is energized by the voltage drop across this armature. The holding coil 29 is connected across armature 1 through wire 36, wire 39, contact 38, contact 20, wire 48, winding 29, terminal N, wire 51, controller arm 50, contact 3, winding 18, wire 45, yoke 14, flexible connector 53, wire 47 and wire 41.

When the switch A moves to the normal position from the reverse, the motor circuit is from terminal BH, through wire 7¹, wire 18, winding 23, wire 33, contact 20, wire 34, wire 32, yoke 14, flexible connector 53, wire 47, wire 41, armature 1, wire 36, wire 35, flexible connector 54, yoke 13, wire 40, winding 16, contact 4, controller arm 50, and field 2 to terminal CH. The holding coil associated with this circuit is winding 28, and it is connected across armature 1 through wire 41, wire 31, contact 56, contact 46, wire 58, winding 28, terminal N, wire 51, controller arm 50, contact 4, winding 16, wire 40, yoke 13, flexible connector 54, wire 35, and wire 36.

In describing the operation of the apparatus, I will assume it is desired to move the switch to the reverse position. Pole-changer L will be reversed, so that current will flow through neutral relay B, thus attracting armature 17 and closing suitable contacts so that the polarity of relay P is reversed, and armature 12 will move to the right in which position it is locked and armature 17 is again released. The movement of armature 12 to the right will move yokes 13, 14 and 15 to the left, completing the motor circuit when armature 17 is released, thereby closing contact 33—34 through contact 20, and the switch will move to the reverse position. If an obstruction occurs in switch A while moving to the reverse position, the motor current will rise above the value necessary to operate thermal relay T¹ and contact 37—38 will open, opening the holding coil circuit. With the holding coil circuit open, armature 26 is not attracted, and armature 21 will be pulled down by the attraction of energized coil 23. Detent 57 will then raise link 19, disengaging slot 43 from pin 42, and arm 70 will move to the right due to the bias exerted by compressed spring 44. Contact 33—34 will there-

fore be opened, opening the motor circuit. The circuit breaker, once having been tripped, will not reset until the controller P has moved to the opposite position. Resetting the circuit breaker is accomplished by reversing pole-changer L, thus energizing neutral relay B and attracting armature 17, and moving link 19 so that slot 43 engages pin 42. Armature 17 will close suitable contacts which energize polar relay P, reversing its polarity, and armature 12 will move to the left, moving yokes 13, 14 and 15 to the right, and the motor circuit will then be completed for reverse rotation when armature 17 is released closing contact 33—34 through contact 20. When the switch returns to the original position, the operation may be repeated as first described.

In a similar manner if the switch is to be moved from the reverse position to the normal, the pole-changer L is moved to the position shown on the drawing, thus energizing neutral relay B and attracting armature 17. Armature 17 will close suitable contacts which energize polar relay P so that armature 12 will move to the left, and yokes 13, 14 and 15 will move to the right, completing the motor circuit when armature 17 is released to close contact 33—34 through contact 20. The switch will then move to the normal position. If an obstruction occurs in switch A while it is moving to the normal position, the motor current will rise above the value necessary to operate thermal relay T, and contact 46—56 will open, opening the holding coil circuit. With the holding coil circuit open, armature 26 will not be attracted, and armature 21 will be pulled down by the attraction of energized coil 23. Detent 57 will then raise link 19, disengaging slot 43 from pin 42, and arm 70 will move to the right due to the bias exerted by compressed spring 44. Contact 33—34 will then be opened, opening the motor circuit. The circuit breaker being tripped will not reset until controller P has moved to the opposite position. Resetting the controller is accomplished by reversing pole-changer L, thus energizing neutral relay B and attracting armature 17 and moving link 19 so that slot 43 engages pin 42. Armature 17 will close suitable contacts which energize polar relay P, reversing its polarity, and armature 12 will move to the right, moving yokes 13, 14 and 15 to the left, and the motor circuit will be completed when armature 17 is released to close contact 33—34 through contact 20. When switch A returns to the original position, the operation may be repeated as before described.

With apparatus embodying my invention, it is possible to restore the switch to its last operated position immediately and to attempt to operate the switch again in the direction in which it failed as soon as the ther-

mal relay for that direction has cooled so as to complete the holding coil circuit.

Although I have herein shown and described only one form of apparatus embodying my invention, it is understood that various changes and modifications may be made therein within the scope of the appended claims without departing from the spirit and scope of my invention.

10 Having thus described my invention, what I claim is:

1. In combination, a railway switch, an electric motor for operating said switch, a normal and a reverse thermal relay each having a heating winding and a normally closed contact, a circuit controller operated by said switch and having a first contact closed in all positions of the switch except the reverse and a second contact closed in all positions 15 of the switch except the normal, a normal operating circuit for said motor including the heating winding of said normal thermal relay and the second contact of said circuit controller, and a reverse operating circuit for 20 said motor including the heating winding of said reverse thermal relay and the first contact of said circuit controller, a circuit breaker having a first and a second core for controlling the supply of current to said motor, 25 a winding on the first core of said circuit breaker included in both of said motor circuits and constituting a means for tripping said circuit breaker, and two windings on the second core of said circuit breaker connected 30 in turn across the armature of said motor and energized through a contact of one or the other of said thermal relays and when energized acting to prevent tripping of said circuit breaker.

35 2. In combination, a railway switch, an electric motor for operating said switch, two thermal relays each having a heating winding and a normally closed contact, two circuits for said motor each including the heating winding of one or the other of said thermal relays, means for supplying current to one of said circuits or the other to cause operation of the motor in one direction or the other, a circuit breaker including a first and a second core for controlling the supply of current to said motor, a winding on the first core of said circuit breaker included in both of said motor circuits and constituting a means for tripping said circuit breaker, and two windings on the second core of said circuit breaker connected in turn across the armature of said motor and energized through a contact of one or the other of said thermal relays and when energized acting to prevent tripping of said circuit breaker.

40 3. In combination with an electric motor, an operating circuit for said motor, a circuit controller for controlling the supply of current to said motor comprising a first and a second core, a winding on said first core in-

cluded in said operating circuit and constituting a means for operating said circuit controller, and means responsive to the magnitude of the current supplied to said motor for governing the flux in said second core to prevent operation of said circuit controller.

4. In combination with an electric motor, an operating circuit for said motor, a circuit controller for controlling the supply of current to said motor comprising a first and a second core, a winding on said first core included in said operating circuit and constituting a means for operating said circuit controller, and thermal means responsive to the magnitude of the current supplied to said motor for governing the flux in said second core to prevent operation of said circuit controller.

5. In combination with an electric motor, a first winding, a governing circuit for said motor including said first winding, a second winding, a circuit controller for controlling the supply of current to said motor and controlled jointly by said two windings, an operating circuit for said second winding, and means responsive to the magnitude of the current in said governing circuit for controlling the operating circuit for said second winding.

6. In combination with an electric motor, a first winding, a governing circuit for said motor including said first winding, a second winding, a circuit controller for controlling the supply of current to said motor and controlled jointly by said two windings, an operating circuit for said second winding, and thermal means responsive to the magnitude of the current in said governing circuit for controlling the operating circuit for said second winding.

7. In combination, an electric motor, two circuits for said motor, means for supplying current to one of said circuits or the other to cause operation of the motor in one direction or the other, a circuit controller for controlling the supply of current to said motor comprising a first and a second core, an operating winding on said first core included in both of said motor circuits and constituting a means for operating said circuit controller, two holding windings on said second core acting when energized to prevent operation of said circuit controller, an operating circuit for each of said holding windings, and means included in each of said motor circuits and responsive to the magnitude of the current supplied to said motor for controlling the operating circuit of the holding winding associated therewith.

8. In combination, an electric motor, two circuits for said motor, means for supplying current to one of said circuits or the other to cause operation of the motor in one direction or the other, a circuit controller for controlling the supply of current to said motor, an operating winding included in both of

said motor circuits and constituting a means for operating said circuit controller, two holding windings acting when energized to prevent operation of said circuit controller, 5 an operating circuit for each of said holding windings, and means included in each of said motor circuits and responsive to the magnitude of the current supplied to said motor for controlling the operating circuit of the holding winding associated therewith.

10 9. In combination, a device movable between a first and a second position, an electric motor for operating said device, a circuit controller operated by said device and having a first contact closed in all positions of the device except the second and a second contact closed in all positions of the device except the first, a first operating circuit for said motor including the second contact of said circuit controller, a second operating circuit for said motor including the first contact of said circuit controller, a circuit breaker for controlling the supply of current to said motor having a first and a second core, an operating winding on said first core included in both of said motor circuits and constituting a means for tripping said circuit breaker, two holding windings on said second core acting when energized to prevent tripping of 30 said circuit breaker, an operating circuit for each of said holding windings, and means included in each of said motor circuits and responsive to the magnitude of the current supplied to said motor for controlling the operating circuit of the holding winding associated therewith.

10 10. In combination, a device movable between a first and a second position, an electric motor for operating said device, a circuit controller operated by said device and having a first contact closed in all positions of the device except the second and a second contact closed in all positions of the device except the first, a first operating circuit for said motor including the second contact of said circuit controller, a second operating circuit for said motor including the first contact of said circuit controller, a circuit breaker for controlling the supply of current to 50 said motor, an operating winding included in both of said motor circuits and constituting a means for operating said circuit breaker, two holding windings acting when energized to prevent operation of said circuit breaker, an operating circuit for each of said holding windings, and means included in each of said motor circuits and responsive to the magnitude of the current supplied to said motor for controlling the operating circuit of the holding winding associated therewith.

11 11. In combination with an electric motor, an operating circuit for said motor, a circuit controller for controlling the supply of current to said motor comprising a first and a second core, an operating winding on said

first core included in said operating circuit and constituting a means for operating said circuit controller, a holding winding on said second core acting when energized to prevent operation of said circuit controller, a control 70 circuit for said holding winding, and means included in said operating circuit and responsive to the magnitude of the current supplied to said motor for governing said control circuit.

12 12. In combination with an electric motor, an operating circuit for said motor, a circuit controller for controlling the supply of current to said motor comprising a first and a second core, an operating winding on said 80 first core included in said operating circuit and constituting a means for operating said circuit controller, a holding winding on said second core acting when energized to prevent operation of said circuit controller, a control circuit for said holding winding, and thermal means included in said operating circuit and responsive to the magnitude of the current supplied to said motor for governing 85 said control circuit.

13 13. In combination, a railway switch, an electric motor for operating said switch, a normal and a reverse thermal relay each having a heating winding and a contact, a circuit controller operated by said switch and having a first contact closed in all positions of the switch except the reverse and a second contact closed in all positions of the switch except the normal, a normal operating circuit for said motor including the heating 95 winding of said normal thermal relay and the second contact of said circuit controller, and a reverse operating circuit for said motor including the heating winding of said reverse thermal relay and the first contact of said circuit controller, a circuit breaker having a first and a second core for controlling the supply of current to said motor, a winding on the first core of said circuit breaker included in both of said motor circuits and constituting a means for tripping said circuit breaker, two windings on said second core acting when energized to prevent tripping of said circuit breaker, and an operating circuit for each of said two windings controlled by a 105 contact of the thermal relay associated therewith.

14 14. In combination, a railway switch, an electric motor for operating said switch, a normal and a reverse thermal relay each 110 having a heating winding and a contact, a circuit controller operated by said switch and having a first contact closed in all positions of the switch except the reverse and a second contact closed in all positions of the switch except the normal, a normal operating circuit for said motor including the heating winding of said normal thermal relay and the second contact of said circuit controller, and a reverse operating circuit for said motor 115

including the heating winding of said reverse thermal relay and the first contact of said circuit controller, a circuit breaker for controlling the supply of current to said 5 motor, an operating winding included in both of said motor circuits and constituting a means for operating said circuit breaker, two holding windings acting when energized to prevent operation of said circuit breaker, and 10 an operating circuit for each of said two windings controlled by a contact of the thermal relay associated therewith.

15. In combination, a railway switch, an electric motor for operating said switch, two 15 thermal relays each having a heating winding and a contact, two circuits for said motor each including the heating winding of one or the other of said thermal relays, means for supplying current to one of said circuits 20 or the other to cause operation of the motor in one direction or the other, a circuit breaker having a first and a second core for controlling the supply of current to said motor, a winding on the first core of said circuit 25 breaker included in both of said motor circuits and constituting a means for tripping said circuit breaker, two windings on said second core acting when energized to prevent tripping of said circuit breaker, and 30 an operating circuit for each of said two windings controlled by a contact of the thermal relay associated therewith.

16. In combination, a railway switch, an electric motor for operating said switch, two 35 thermal relays each having a heating winding and a contact, two circuits for said motor each including the heating winding of one or the other of said thermal relays, means for supplying current to one of said circuits 40 or the other to cause operation of the motor in one direction or the other, a circuit breaker for controlling the supply of current to said motor, an operating winding included in both of said motor circuits and constituting 45 a means for tripping said circuit breaker, two holding windings acting when energized to prevent tripping of said circuit breaker, and an operating circuit for each of said holding windings controlled by a contact of the 50 thermal relay associated therewith.

In testimony whereof I affix my signature.

BERNARD E. O'HAGAN.
